CRIB BLANKET

Elisabeth A. Gunnill, Bayport, N. Y.

Application August 4, 1949, Serial No. 4,292

Term of patent 14 years

(Cl. D92—2)

To all whom it may concern:

Be it known that I, Elisabeth A. Gunnill, a citizen of the United States, residing at Bayport, county of Suffolk, and State of New York, have invented a new, original, and ornamental Design for a Crib Blanket, of which the following is a specification, reference being had to the accompanying drawing, forming a part hereof.

Fig. 1 is a face view of a crib blanket, showing my new design; and

Fig. 2 is a vertical sectional view thereof taken on line 2—2 of Fig. 1.

I claim:

The ornamental design for a crib blanket, as shown.

ELISABETH A. GUNNILL.
